(57) **CLAIM**

The ornamental design for a cap arrangement for a bottle, as shown and described.

DESCRIPTION

FIG. 1 is a rear perspective view of a cap arrangement for a bottle with the lid in an open condition, showing an embodiment of my new design;

FIG. 2 is a front perspective view of the embodiment shown in FIG. 1;

FIG. 3 is a rear view of the embodiment shown in FIG. 1; FIG. 4 is a front view of the embodiment shown in FIG. 1; FIG. 5 is a right side view of the embodiment shown in FIG. 1;

FIG. 6 is a left side view of the embodiment shown in FIG. 1;

FIG. 7 is a cross sectional view of the embodiment shown in FIG. 1, shown along line 7—7 of FIG. 2;

FIG. 8 is a bottom view of the embodiment shown in FIG. 1 with the lid in an open condition;

FIG. 9 is a top view of the embodiment shown in FIG. 1 with the lid in an open condition;

FIG. 10 is a bottom view of a variation of the embodiment shown in FIG. 8 with the lid in an open condition;

FIG. 11 is a top view of the embodiment shown in FIG. 10 with the lid in an open condition;

FIG. 12 is a rear view of the top portion of the embodiment shown in FIG. 1 with the lid in a closed condition, shown separately for ease of illustration.

FIG. 13 is a side view of the top portion of the embodiment shown in FIG. 1 with the lid in a closed condition, shown separately for ease of illustration.

FIG. 14 is a right side view of the embodiment shown in FIG. 10; and,

FIG. 15 is a left side view of the embodiment shown in FIG. 10.
